United States Patent Office

Des. 192,241
Patented Feb. 20, 1962

192,241

ORNAMENT FOR AUTOMOBILES OR THE LIKE

Arthur R. Vogel, 458 S. Clark St., Powell, Wyo.

Filed Feb. 9, 1961, Ser. No. 63,877

Term of patent 14 years

(Cl. D14—6)

FIG. 1

FIG. 3

FIG. 2

FIG. 4

FIG. 1 is a perspective view of an ornament for automobiles or the like, showing my novel design.

FIG. 2 is an elevational view thereof showing the side opposite that shown in FIG. 1;

FIG. 3 is a front elevational view thereof; and

FIG. 4 is a top plan view thereof.

The characteristic features of my design reside in the portions shown by means of solid lines in the drawing.

I claim:

The ornamental design for an ornament for automobiles or the like, substantially as shown and described.
